UNITED STATES PATENT OFFICE

GEORGE H. ISLEY, OF WORCESTER, MASSACHUSETTS, ASSIGNEE TO MORGAN CONSTRUCTION COMPANY, OF WORCESTER, MASSACHUSETTS, A CORPORATION OF MASSACHUSETTS.

FEEDING MECHANISM FOR GAS-PRODUCERS.

984,675.

Specification of Letters Patent. Patented Feb. 21, 1911.

Application filed August 11, 1909. Serial No. 512,335.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Feeding Mechanism for Gas-Producers, of which the following is a specification, accompanied by drawings forming a part of 10 the same, in which—

Figure 1 represents a plan view of a gas producer embodying my invention. Fig. 2 is a vertical sectional view of the feeding mechanism on the plane of the broken line 15 2—2, Fig. 1, and Fig. 3 is a detached perspective view of one of the adjustable coal distributors.

Similar reference characters refer to similar parts in the different figures.

20 My present invention relates to the coal feeding mechanism of a gas producer, having for its objects to accomplish a more uniform and efficient distribution of the coal to the gas producing chamber and to bring the 25 distribution within the control of the operator, and I accomplish these objects by the construction and arrangement of parts as hereinafter described and pointed out in the annexed claims.

30 Referring to the accompanying drawings, 1 denotes the upper portion of the gas producing chamber inclosed by walls 2, upon which is mounted a cover 3, preferably pan shaped, to contain water to avoid the 35 injurious effects due to over heating. The cover 3 is provided with a series of openings 4 closed by covers 5, which are water sealed by the body of water 6 contained in the cover 3. The openings 4 allow the interior 40 of the gas producing chamber 1 to be inspected to determine the condition of the fuel and to observe its distribution. Mounted upon the cover 3 is a platform 7, upon which coal is delivered through the hopper 45 shaped opening 8 from the magazine 9.

Journaled in the platform 7, concentrically with the gas producing chamber, is a spindle 10. To the lower end of the spindle 10 is attached a ratchet wheel 11, actuated by 50 a pawl 12 pivotally attached to a reciprocating bar 13. The bar 13 is pivotally connected with a block 14 pivoted at 15 to a bracket 16. Vertically adjustable in the block 14 is a rod 17 having a handle 18 at

its upper end, by which it may be raised or 55 lowered in the block 14, and held in position by a set screw 19. The lower end of the rod 17 is connected by a link 20 with an eccentric strap 21 inclosing an eccentric 22 carried upon a rotating shaft 23, which is 60 driven by a belt pulley 24 through a belt connection 25 with a suitable source of power. The vertical adjustment of the rod 17 in the block 14 varies the amount of reciprocating movement of the bar 13, causing 65 the pawl 12 to slide over one or more teeth according to the speed it is desired to give to the rotating spindle 10. Upon the upper end of the spindle 10 are attached blades 26, which extend over the surface of the platform 7 and serve to push the coal from the center of the platform toward its periphery and, for this purpose, the blades 26 are preferably curved, as shown by the broken lines 70 27, Fig. 1, and they are rotated in the direction of the arrow 28, Fig. 1.

Near the periphery of the platform 7 are a series of openings, one of which is shown at 29, Fig. 2, said openings being in alignment with similar openings in the cover 3, 80 one of which is shown at 30, Fig. 2. Mounted upon the platform 7 is a cover 31 having a depending flange 32, which rests upon the platform 7 inside an upturned flange 33 on the edge of the platform 7. The cover 31 85 is also provided with an upturned flange 34 forming a pan shaped receptacle for water. The cover 31 is also provided with a series of concentric openings, one of which is shown at 35, Fig. 2, in alignment with the openings 90 29 of the platform 7. The openings 35 are surrounded by an upturned flange 35^a, extending above the line of the water on the cover 31 and supporting a downwardly flanged cover 36, by which the cover is water 95 sealed.

Depending from the under side of the cover 36 is a coal distributor 37, which is shown in detached perspective view in Fig. 3. The upper portion of the distributor 37 100 is vertical and substantially semicircular in cross section, and is provided at its upper end with a flange 38 having a bolt hole 39 by which it is attached to the cover 36. The lower end of the coal distributor is provided 105 with an inclined chute 40 having, through a portion of its length, the side flanges 41, 41. The vertical semicircular section of the coal

distributer 37 extends downward through the openings 25 and 29 and is maintained, by its attachment to the cover 36, near the peripheries of the openings 35 and 29. The 5 inclined chute 40 projects downward at an oblique angle through the opening 30 in the cover 3. The opening 30 is inclosed by a flaring flange 42, forming an inverted hopper shaped space for the free delivery of 10 coal from the chute 40 into the gas producing chamber. The upper end of the flange 42 is cylindrical and is provided with an interior shoulder 43, which supports the depending flange 44 inclosing the opening 29. 15 The magazine 9 is a cylindrical shell which rests upon the cover 31 concentrically with the hopper shaped opening 8. The cover 31 is turned upwardly at 45 to form a flange which is inclosed by the lower end of the 20 magazine 9. The flange 45 is then bent downwardly at an oblique angle to form the hopper shaped opening 8.

The operation of my improved feeding mechanism is as follows:—Coal contained 25 in the magazine 9 falls through the hopper shaped opening 8 and is supported upon the platform 7. Rotary motion is imparted to the blades 26, causing the coal resting upon the platform 7 to be pushed radially outward until it falls through one of the series 30 of openings 29. As the coal falls through the openings 29 it is caught upon the inclined chute 40, from which it slides at an oblique angle and becomes distributed over 35 the mass of fuel in the gas producing chamber 1. An examination of the gas producing chamber, which may be made by removing either of the covers 5 or 36, will disclose the distribution of coal and, if this is 40 not sufficiently uniform, it may be varied by rotating the covers 36 on their supporting flanges 35, thereby swinging the coal distributors 37 and changing the direction of the inclined chutes. An adjustment of a 45 sufficient number of covers 36 is made to effect a uniform distribution of coal over the incandescent mass of fuel in the gas producing chamber. If it be found that the combustion of fuel is proceeding in certain spots 50 more rapidly than in others, the appropriate coal distributors are rotated in their respective openings to cause their inclined chutes to deliver an increased supply of coal thereto. The formation of air flues or "pipes" in 55 the mass of fuel is thereby avoided and a uniform combustion throughout the entire mass of fuel is maintained.

The magazine 9 is water sealed at its lower end, as are also the covers 5 and 36. 60 The joints between the flanges 32 and 33 and the flanges 42 and 44 are luted. The cover 3 and the operative mechanism mounted thereon are protected from excessive heat by the body of water 6. The platform 7, cover 65 31 and magazine 9 are individually or col-

lectively removable without the use of bolts, forming a simple and inexpensive construction.

I claim.

1. In a feeding mechanism for gas producers, a gas producing chamber, a cover therefor, having a series of concentric openings, a platform above said cover having a series of concentric openings in alignment with the openings in said cover, a second 75 cover for said platform inclosing a circular chamber, rotating blades in said chamber extending over said platform, and means between said platform and the cover of the gas producing chamber for rotating said 80 blades.

2. In a feeding mechanism for gas producers, a gas producing chamber, a dish shaped cover therefor provided with a water space, a platform supported above said 85 cover, means for supplying coal to the center of said table, a cover for said table inclosing a circular chamber, a series of concentric inclosed coal passages leading from the upper surface of said table to the gas producing chamber, a spindle journaled in said platform, rotatable blades carried by said spindle above said platform, and means inclosed in said dish shaped cover for rotating 90 said spindle.

3. In a feeding mechanism for gas producers, a gas producing chamber, a water receptacle forming a cover for said chamber, a platform mounted above said cover, a spindle journaled in said platform concentric with the gas producing chamber, rotatable blades carried by the upper end of said spindle above said platform, means for rotating said spindle below said platform, and a series of concentric inclosed coal 100 passages leading from the upper surface of said platform to said gas producing chamber. 105

4. In a feeding mechanism for gas producers, a water receptacle forming a cover for said chamber, a horizontal platform mounted above said cover, a horizontal cover for said platform inclosing a circular chamber concentric with the gas producing chamber, a spindle journaled concentrically with the gas producing chamber, rotatable blades 110 carried by said spindle and inclosed in said circular chamber, means for delivering coal to the center of said platform, a series of inclosed coal passages leading from the upper surface of the platform to the gas producing chamber, and a series of water sealed openings in the cover of said platform in alignment with said inclosed coal passages. 115

5. In a feeding mechanism for gas producers, a gas producing chamber, a dish shaped cover therefor, a platform mounted above said cover, a spindle journaled concentrically with the gas producing chamber, rotatable blades carried by said spindle above said platform, an inclosed chamber 120 125

130

concentric with the gas producing chamber and, containing said rotatable blades, a hopper mounted above said inclosed chamber and communicating therewith, and a series 5 of inclosed coal passages leading from the upper surface of said platform to the gas producing chamber.

6. In a feeding mechanism for gas producers, a platform mounted above the gas 10 producing chamber, a series of coal passages leading from the upper surface of said platform to the gas producing chamber, means for moving coal from said platform through said coal passages, and fixed chutes adjustably held in said coal passages for changing 15 the direction of the coal in each of said passages independently of the other passages.

7. In a feeding mechanism for gas producers, a gas producing chamber, a cover 20 therefor having a series of coal passages concentric with the gas producing chamber, means for supplying coal to said passages, and chutes held in each of said coal passages in a fixed position for changing the direction 25 of the coal independently in each of said passages.

8. In a feeding mechanism for gas producers, a gas producing chamber, a cover 30 therefor, a platform mounted above said cover, a series of coal passages leading from the upper surface of said platform to the gas producing chamber, means for supplying coal to said coal passages, and chutes obliquely inclined to a horizontal plane held 35 in a fixed position in said coal passages and rotatably adjustable therein.

9. In a feeding mechanism for gas producers, a gas producing chamber, a cover 40 therefor having a series of concentric openings for the admission of coal to the gas producing chamber, and means for independently changing the direction of coal in each of said openings.

10. In a feeding mechanism for gas producers, a platform for supporting the coal 45 to be fed to the producer, a series of concentric coal passages leading from said platform to a gas producing chamber, a cover for said platform inclosing a concentric chamber and having a series of openings in 50 alinement with said coal passages, water sealed covers for said openings, and chutes suspended from said covers and extending into said coal passages, each of said chutes being independently adjustable. 55

11. In a feeding mechanism for gas producers, a gas producing chamber, a cover therefor, a platform mounted above said cover, a second cover for said platform inclosing a coal chamber, said second cover 60 having a flange turned vertically upward and obliquely downward to inclose a hopper shaped opening, a coal reservoir mounted on said cover above said hopper shaped opening, a series of concentric coal passages leading from the upper surface of said platform to the gas producing chamber, and means for moving coal from said platform through said passages. 65

12. In a feeding mechanism for gas producers, a gas producing chamber, a cover 70 therefor having a series of passages for the admission of coal to the gas producing chamber concentric therewith, a horizontal platform for supporting the coal to be fed, 75 a rotatable spindle journaled at right angles with said platform, blades carried by said spindle above said platform, means for imparting an intermittent movement to said spindle, and means for varying the extent 80 of each movement of the spindle.

Dated this seventh day of August 1909.
